ROASTING FURNACE

Friedrich Johannsen, Magdeburg, Germany

Application February 9, 1934, Serial No. 710,511
In Germany February 15, 1933

7 Claims. (Cl. 263—32)

My invention relates to the problem of roasting exhaustively and under conditions of economy zinc-blend and other ores, which contain sulfur, arsenic, antimony, etc. in varying quantities, and 5 which because of their liability to frit and coalesce at relatively low temperatures and because of other adverse conditions, known to practitioners, are difficult in practice to be thoroughly desulfurized and completely roasted in metallurgical furnaces of known design including those of 10 the rotary tubular types.

It has been attempted by the inventor to roast zinc blend in a rotary tubular furnace of the ordinary single chamber type by causing the charge 15 to pass through the furnace in an unusually thick layer so as not too frequently come into contact with the oxidizing air, in order to prevent a too rapid and violent combustion of the sulfur in the charge and thus to avoid the production of excessive heat.

The results however have been unsatisfactory inasmuch as, after the bulk of the sulfur has been burnt in the middle section of the furnace, the sulfur content retained in the charge, while 25 the latter proceeds towards the exit of the furnace gradually becomes inadequate for being kept burning. In other words: The relatively small balance of the sulfur—about 4-7%—cannot be burnt because of the very thickness of the 30 layer of the charge and its inadequate contact with the oxidizing air.

Moreover additional heat from without in the form of combustion gases carrying with them an excess of air cannot be applied to the charge approaching the exit of the furnace, because the 35 sulfurous acid issuing from the furnace, which it is compulsory by law to collect in Germany and other countries, is mostly used for the production of sulfuric acid and therefore must be kept free from contamination with carbonic acid and nitrogen of which the said combustion gases are composed.

Further efforts and suggestions made by other inventors how to re-design the single chamber 45 rotary tubular furnace so as to convert it into an efficient roasting furnace, from which an exhaustively roasted product is obtained, which should be entirely free from sulfur, include the provision of an expansion chamber, of air pipe 50 systems, automatic valves—four way cocks—air ducts, scoops etc. for the timely introduction of air into different sections of the furnace, as described for instance in the U. S. Letters Patent 1,791,403 and 1,830,002.

55 The invention disclosed hereinafter also aims

at overcoming the aforesaid difficulties by providing for the specific purpose of exhaustively roasting zinc-blend and other materials of the character described—a structurally improved rotary tubular furnace of relatively simple design—which can be erected and operated at relatively low cost, being distinguished from roasting furnaces used or proposed heretofore by the absence of any complicated, moveable and costly 10 accessory parts.

In connection therewith the invention aims at so re-designing a rotary tubular furnace of the single chamber type for the purposes indicated that its manner of working, viz. the heat produced and the reactions occurring in its different 15 sections or zones can be easily controlled, modified and adapted at short notice to varying conditions brought about for instance by accidental changes in the sulfur or iron content of the ore etc., so as to ensure a complete desulfurization of 20 the material under treatment.

Other objects involved in this invention will become incidentally apparent hereinafter to practitioners in this field.

The nature and scope of the invention are 25 briefly outlined in the appended claims and will be more fully understood from the following specification taken together with the accompanying drawing in which

Fig. 1 is a section longitudinally taken on line 30 I—I in Fig. 2 through a roasting furnace designed according to this invention,

Fig. 2 is a cross section, taken through the furnace on line II—II in Fig. 1 and being drawn on a slightly larger scale,

35 Figs. 3—5 are cross sectional views corresponding to Figure 2 and showing by way of examples structurally modified roasting furnaces designed according to this invention.

With the objects in view set forth above the 40 structurally improved roasting furnace comprises a rotary shell S open at both ends, which is lined with refractory material and is subdivided at its lower end for a portion of its length into a plurality of chambers for the purpose described in 45 detail hereinafter.

The furnace is preferably mounted at a small angle of inclination—ranging about 1½ percent—so as to enable the charge to pass, while the furnace rotates at a moderate rate of speed, 50 in a relatively thick layer L through the single chamber sections A, B of the furnace. The total length of said sections A, B is so chosen, that the charge, while passing through section A is gradually heated up to the point of inflamma- 55

tion by the hot combustion gases produced in section B, in which the bulk of the sulfur and other combustible matter in the charge is burnt.

Feeding means F are provided at the upper end 5 of the furnace for delivering the charge into the single chamber section A.

One of the most salient features of the invention consists therein, that the furnace is longitudinally subdivided at its lower end for a portion 10 of its length into a plurality of chambers, collectively hereinafter called multiple-chamber section, and being designated C, which is preferably in direct and open communication with the single chamber section B.

15 As seen in Fig. 1 by the provision of a plurality of chambers in section C of the furnace the charge, which has passed through sections A, B in a relatively thick layer L, is split up into a number of smaller currents of smaller thickness 20 with the result, that a larger surface of the charge than before is exposed to the oxidizing air, whereby the charge, being trundled around and agitated, is more frequently and intimately brought into contact with the air. As the sulfur content has already been materially reduced 25 in the main roasting zone B, the danger of the charge getting overheated in the final roasting zone C, which would occur if the preliminary and main roasting zones A, B were of like formation, is avoided.

The inventor's experimental work has shown, that the best results are obtained, if the length 30 of the multiple chamber section C does not exceed one third of the total length of the furnace, and that the charge is capable of ridding itself 35 in the final roasting zone from all the balance of sulfur, arsenic and other undesirable constituents.

According to this invention means are provided 40 enabling the operator to control the heat developed and the reactions occurring in the furnace, so as to ensure its steady operation and a substantially uniform quality of the roasted product.

45 In their preferred embodiment said heat controlling means comprise

(1) An air duct D, axially extending through the central portion of the multiple chamber section C, and an air pipe P, which is conveniently 50 provided with a valve and is connected with a fan, not shown, by which cold or preheated air—according to requirements—can be blown directly into the single chamber section B of the furnace.

(2) Burners U, U2 for the admission of gaseous, liquid or pulverulent fuel, by which the furnace is heated up on being set into operation, and by which in cases of emergency additional heat can be applied to the charge;

(3) Instead of providing burners U, U2, hot air—if available—may be conveniently introduced into the furnace through an air conduit T leading into the hood H, which encloses the exit end of the furnace.

Various other changes and modifications may 65 be made in the design and structural details of roasting furnaces of the improved type described hereinbefore, without departing from the spirit and the salient ideas of this invention:

As seen in Figs. 3 and 4 the outer walls of the 70 chambers of the final roasting zone C may be provided with extra thick or additional linings i, i2 with the object of materially reducing the aggregate diameter of the chambers in the final roasting zone C and thus forming a step or baffle 75 ring, in front of which the charge is dammed up

and is collected in a thick layer; this simple expedient allows of re-constructing and using to equal advantage rotary tubular furnaces for the purposes of this invention which are mounted at a steeper angle than 1½ percent, specified above.

Instead of chambers having a cross sectional shape of a sector—shown in Figs. 2, 3, 5—circular or oval shaped chambers o, o2 shown in Fig. 4, 10 may be conveniently used in the final roasting zone C.

Chambers of circular cross sectional shape o have been found to be preferable in cases, where the ores under treatment tend to become overheated during the roasting process.

Instead of four or five chambers, shown in the 15 drawing, any other convenient number may be provided in the multiple chamber section C of the furnace consistent with the diameter of the latter and the nature of the material to be roasted.

Oxidizing air instead of being blown into the 20 furnace through air duct D may be conveniently drawn thereinto by natural or suction draft.

Good results have been obtained in practice with a tubular rotary furnace designed according to this invention for roasting flotation zinc-blend, the granules of which would pass through a 25 sieve having 60 meshes; the diameter of the outer shell of the furnace being about 2 meters, its total length 20 m., the length of the multiple chamber section 5 m.; the thickness of the refractory lining in the single chamber section being 150 mm. and of that in the multiple chamber section 300 mm.; the latter containing 6 chambers.

What I claim is:—

1. In a tubular rotary furnace for roasting ores, the combination with a shell having a lining of refractory material and presenting a single chamber section at the intake end of the furnace, of a multiple chamber section formed at the outlet end 40 of the furnace, and means for separately introducing reaction agents into the multiple and the single chamber sections of the furnace from the outlet end of the latter.

2. In a tubular rotary furnace for roasting ores, the combination with a shell having a lining of refractory material and presenting a single chamber section at the intake end of the furnace, of a multiple chamber section formed at the outlet end of the furnace, and means for separately introducing reaction agents into the multiple and the single chamber sections of the furnace from the outlet end of the latter, said means comprising a hood enclosing the outlet end of the furnace, an air duct and pipes cooperatively associated with said hood for feeding reaction agents into the multiple chamber section of the furnace and another air duct longitudinally extending through the multiple chamber section for feeding reaction agents into the single chamber section.

3. In a tubular rotary furnace for roasting ores, the combination with a substantially cylindrical shell having a lining of refractory material and presenting a single chamber section at the intake end of the furnace, of a multiple chamber section formed at the outlet end of the furnace, and means for damming up the charge in front of the multiple chamber section.

4. In a tubular rotary furnace for roasting ores, the combination with a substantially cylindrical shell having a lining of refractory material and presenting a single chamber section at the intake end of the furnace, of a multiple chamber section formed at the outlet end of the furnace, and means for damming up the charge in front of the mul-

multiple chamber section, said means comprising refractory linings which are of greater thickness in the multiple chamber section than in the single chamber section of the furnace.

5. In a tubular rotary furnace for roasting ores, a rotary shell having a single chamber zone within which the ore is initially treated for removing the major portion of the undesirable constituents, a plurality of separate chambers arranged in the outlet zone of the shell for receiving the previously treated ore from the single chamber so that an increased contact is effected between the charges in the separate chambers with air and reaction agents, means for supplying the ore to be treated into the single chamber zone, a hood the interior of which is in permanent communication with all of the separate chambers, and which has means for supplying air into the hood, and means for supplying reaction agents into the hood.
6. In a tubular rotary furnace for roasting ores, a rotary shell having a single chamber zone within which the ore is initially treated for removing the major portion of the undesirable constituents, a plurality of separate chambers arranged in the outlet zone of the shell for receiving the previously treated ore from the single chamber so that an increased contact is effected between the

charges in the separate chambers with air and reaction agents, means for supplying the ore to be treated into the single chamber zone, a hood the interior of which is in permanent communication with all of the separate chambers and which has means for supplying into the hood air and other reaction agents.

7. In a tubular rotary furnace for roasting ores, a rotary shell having a single chamber zone within which the ore is initially treated for removing the major portion of the undesirable constituents, a plurality of separate chambers arranged in the outlet zone of the shell for receiving the previously treated ore from the single chamber so that an increased contact is effected between the charges in the separate chambers with air and reaction agents, means for supplying the ore to be treated into the single chamber zone, a hood the interior of which is in permanent communication with all of the separate chambers and which has means for supplying into the hood air and other reaction agents, and means extending through the outlet zone of the shell and separate from the plurality of separate chambers for supplying air into the single chamber zone of the furnace.

FRIEDRICH JOHANNSEN.
